(57) **CLAIM**

The ornamental design for a display device, as shown and described.

DESCRIPTION

FIG. 1 is a perspective view of a display device showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged view of a portion of FIG. 1;

FIG. 9 is an enlarged view of a portion of FIG. 2;

FIG. 10 is an enlarged view of a portion with a group of screw heads of FIG. 3;

FIG. 11 is an enlarged view of a portion with a screw head of FIG. 3;

FIG. 12 is an enlarged view of a portion with a screw head close to a side of FIG. 3;

FIG. 13 is an enlarged view of a portion with screw heads arranged in a strip of FIG. 3;

FIG. 14 is an enlarged view of a portion of FIG. 4;

FIG. 15 is an enlarged view of the area indicated in FIG. 4;

FIG. 16 is an enlarged view of the area indicated in FIG. 5;

FIG. 17 is an enlarged view of the area indicated in FIG. 6;

and

FIG. 18 is an enlarged view of a portion of FIG. 7.

The evenly dashed broken lines in the figures depict portions of the display device that form no part of the claimed design. The broken lines indicating outer limits of enlarged views in FIGS. 1-18 form no part of the claimed design.
